UNITED STATES PATENT OFFICE.

JOHN C. RUCH AND REUBEN BROUSE, OF NORTHUMBERLAND,
PENNSYLVANIA.

CAR-COUPING.

SPECIFICATION forming part of Letters Patent No. 396,237, dated January 15, 1889.

Application filed September 29, 1888. Serial No. 286,781. (No model.)

To all whom it may concern:

Be it known that we, JOHN C. RUCH and REUBEN BROUSE, citizens of the United States, residing at Northumberland, in the county of Northumberland and State of Pennsylvania, have invented a new and useful Improvement 5 in Car-Couplers, of which the following is a specification.

The invention relates to improvements in 10 automatic car-couplers; and it consists in the construction and novel combination of parts, hereinafter described, illustrated in the accompanying drawings, and pointed out in the appended claims.

15 Figure 1 of the drawings represents a perspective view of a car with a coupler embodying the invention attached, the yoke-links being turned back. Fig. 2 represents a front or face thereof. Fig. 3 represents a side view of 20 the same.

Referring to the drawings by letter, A designates the draw-bar of a car-coupler, and B the draw-head on the outer end thereof, which draw-head is a solid rectangular block with 25 two lateral outwardly-standing ears, b b.

C C are the coupling-hooks, each having its heel pivoted between the ears b b of the corresponding draw-head, so that it will turn up and down thereon. The hook has at its outer 30 end the triangular head c inclined or beveled from its transverse outer edge both upward and downward, and having its rear surfaces, c' c', inclined outward toward the free end of the hook, so that the said surfaces of opposing hooks will catch and hold on each other 35 more securely.

D is an arm standing laterally from one side of the shank of each coupling-hook, for a purpose hereinafter explained, and d is a rectangular supporting-bracket depending from 40 a suitable part of the car and holding the shank of the corresponding hook, which rests within said bracket horizontally, so that the hooks cannot fall apart.

45 E is a yoke-link roughly V-shaped, and with its end formed into loops and pivoted on a bolt passed through a transverse opening in the head c, the head of the bolt retaining the loop in place at one end of the yoke-link, while 50 that at the other end is similarly retained by

a pin passed through a transverse opening in the bolt. The head c might have studs cast integrally on each side as a substitute for the bolt. The yoke-link can be coupled to a draw-head of ordinary construction, as it can enter 55 said draw-head and be secured therein by a pin in the ordinary manner.

F is a transverse shaft journaled in proper bearings secured to the car, and provided at its ends with the crank-handles f f to the outer 60 side of the train.

The shaft F is provided at a proper point with an arm, G, which has its end connected by a chain, g, with the arm D, so that by means of the crank-handles f the corresponding coupling-hook can be raised and uncoupled by the brakeman standing on the ground at the side 65 of the train.

H is a double-armed transverse lever pivoted to a support, h, standing at a proper point 70 of the platform; and I is a vertical rod extending through proper bearings attached to the car at proper points and having the horizontally-bent arm i thereabove. One arm of said lever can be pressed down by the foot of the 75 brakeman on the platform raising the other arm and the corresponding coupling-hook by means of the chain i, that connects said arm that is raised and the arm D on said hook. By means of the rod I the coupling-hook can 80 be raised from the top of the car.

The head c of one coupling-hook lies above and engages that of the other and must be lifted to uncouple therefrom.

The coupler is simple and strong of construction, and can be operated from either side of the train, the top of the car, or the platform thereof. Before two hooks are coupled together the yoke-links are turned back onto the upper surfaces of their shanks. 85

Having described our invention, we claim—

1. The combination of the draw-head, the coupling-hook pivoted thereto and having the triangular head, and the V-shaped link having its ends pivoted to the opposite sides of 95 the said triangular head, as set forth.

2. The combination of the draw-head, the coupling-hook pivoted thereto, the arm D, projecting laterally from the side of the coupling-hook, the rock-shaft arranged above the coup- 100

ling-hook and having an arm, G, and the chain connecting the arms D G, as set forth.

3. In a car-coupler, the combination, with the draw-heads having the lateral ears *b*, the pivoted coupling-hooks having the triangular heads *c* and lateral arms D, and the supporting-brackets, of the double-armed lever H, pivoted on the support *h*, the vertical rod I, having the handle *f* above the car, and the chain *i*, connecting the arm D and the adjacent arm of the lever H, substantially as specified.

In testimony that we claim the foregoing as our own we have hereto affixed our signatures in presence of two witnesses.

JOHN C. RUCH.
REUBEN BROUSE.
